WINDOW SHADE

Waldo M. Streby, North Canton, Ohio

Application May 12, 1938, Serial No. 207,522

11 Claims. (Cl. 156—17)

The invention relates to the type of window shades commonly known as Venetian blinds or shades comprising a plurality of slats adapted to be tilted at various angles to obtain the desired 5 lighting effect in a room, depending upon the position and intensity of the sunlight.

An object of the invention is the provision of a shade of the character referred to in which mechanism is provided for moving the several 10 slats laterally across a window opening and then simultaneously tilting all of the slats to any desired angle.

Another object is to provide a shade of this character in which the slats extend vertically 15 across the window opening.

A further object is to provide such a shade in which two sets of slats are arranged to be moved toward or from each other from opposite sides of the window opening.

20 A still further object is to provide a shade of the type above referred to in which the slats are adapted to be moved across the window opening and tilted to the desired angle by means of a series of lazy tongs and a threaded shaft.

25 The above objects together with others which will be apparent from the drawings and following description, or which may be later referred to may be attained by constructing the improved window shade in the manner illustrated in the 30 accompanying drawings, in which:

Figure 1 is an elevation of the improved shade applied to a window, showing the lazy tongs in the fully extended position and the slats in the fully open position.

35 Fig. 2, an enlarged fragmentary, top plan view of the improved shade showing the same in the fully retracted position.

Fig. 3, a fragmentary elevation of the shade in the same position as shown in Fig. 2.

40 Fig. 4, a fragmentary top plan view of the shade showing the lazy tongs in the fully extended position and the slats tilted to closed position.

Fig. 5, a fragmentary elevation of the shade in the same position as shown in Fig. 4.

45 Fig. 6, a fragmentary top plan view of the shade in the same position as shown in Fig. 1.

Fig. 7, a fragmentary elevation of the portion of the shade in the position shown in Fig. 6.

50 Fig. 8, an enlarged transverse section taken as on the line 8—8, Fig. 7.

Fig. 9, an enlarged transverse section taken as on the line 9—9, Fig. 5.

55 Fig. 10, an enlarged transverse section taken as on the line 10—10, Fig. 7, and

Fig. 11, a fragmentary section taken as on the line 11—11, Fig. 10.

Similar numerals refer to similar parts throughout the drawings.

The improved shade to which the invention 5 pertains is of the general character or type of the well-known Venetian blind, being formed of a plurality of parallel slats arranged to be tilted to any desired angle.

Generally the invention consists in providing 10 rods at two opposite sides of a window opening, a series of lazy tong levers being associated with each rod and carrying a plurality of spaced brackets slidable upon the rods, the slats being axially pivotally connected to these brackets. 15

The shade may be constructed with the slats located horizontally across the window opening as in the case of the ordinary Venetian blind, but in the preferred form of the invention, as illustrated in the accompanying drawings and hereinafter described in detail, the slats may be located vertically and arranged in two sets or series so that they may be retracted toward, or extended from opposite sides of the window opening in much the same manner as the ordinary window curtains or drapes. 25

In the preferred embodiment of the invention as illustrated in the drawings a horizontal rod 15 is located at the top of the window opening being journaled in brackets 16 which may be attached to the window frame in any suitable manner and a similar rod 17 may be located at the bottom of the window opening and journaled in brackets 18 attached to the window frame. 30

In order to provide for simultaneously operating two sets or series of slats at opposite sides of the window opening, each of the rods 15 and 17 may have a right hand thread in the form of a groove 19 upon substantially one-half of its length and a left hand thread in the form of a 40 groove 20 on the other half of its length.

Two sets or series of lazy tong levers 21 and 22 are associated with the left and right hand portions respectively of the upper rod 15. A plurality of equally spaced brackets of channel shape as shown at 23 is connected to each of the sets of lazy tong levers preferably by means of the pins 24 which pivotally connect each crossed pair of the levers, and these brackets are provided 45 with suitable apertures through which rod 15 is located for relative rotatable and slidable movement.

The outer end of each of the lazy tongs 21 and 22 is pivotally connected to an angular bracket 50

25 which has a suitable aperture 26 through which the rod 15 is located.

The angular end portion of this bracket 25, through which the rod is located, is best shown 5 in Fig. 11 located substantially in contact with the adjacent attaching bracket 16 and a friction washer 27 formed of leather, fiber or other suitable friction material is interposed between the bracket 25 and the collar 28 which is fixed upon 10 the rod 15.

A corrugated spring washer 29 is located between the bracket 16 and the collar 30 fixed upon the rod 15 and carrying the sprocket wheel 31. This spring washer thus tends to hold the rod 15 15 in frictional contact with the bracket 25 through the friction washer 27 and collar 28.

A sleeve or bushing 32 is connected at its ends to the spaced ears of each channel bracket 23 and the innermost bracket of each set or series 20 has a pin or stud 33 carried by said sleeve or bushing and extended into spiral groove 19 or 20, as the case may be, in the rod 15 so as to extend or retract the lazy tong levers depending upon the direction in which the rod 15 is rotated.

25 For the purpose of connecting the slats 34 to the brackets 23 a ring 35 is rotatably mounted upon each sleeve or bushing 32 and provided with a depending end portion 36 upon which the corresponding slat 34 is axially rotatably mounted 30 as by a channel clip 37 fixed to the upper end of the slat, the depending end 36 of the ring being journaled through the upper portion of said clip and provided with a head 38.

For the purpose of tilting these slats axially an 35 arm 39 is provided upon each channel bracket 23 and a link 40 is connected at one end to said arm and at the other end to an ear 41 formed at the upper end of the corresponding slat and at the opposite side of the pivotal center of the slat 40 from the arm 39.

Two sets or series of lazy tong levers 21a and 22a corresponding respectively to the lazy tongs 21 and 22 are associated with the lower rod 17 and each has connected thereto at intervals 45 channel brackets 23a corresponding in construction and location to the brackets 23 of the upper mechanism.

The lower ends of the slats 34 have channel 50 clips 37a connected thereto to which are swivelled the upright extensions 36a of the rings 35a. Thus the lower ends of the slats are guided and moved in unison with the upper ends when the two rods 15 and 17 are simultaneously rotated by means of the endless chain 42 located over 55 the sprockets 31 and 31a of the shafts 15 and 17 respectively.

In the operation of the improved shade, assuming the parts to be in the position shown in Figs. 2 and 3 with the lazy tongs in the retracted 60 position and the slats turned edgewise with respect to the window opening, the rods 15 and 17 may be simultaneously rotated by means of the chain 42 in a direction to extend the lazy tongs and separate the channel brackets 23 and 23a carrying the slats.

As the upper rod 15 is rotated in this direction the lazy tongs will be moved from a vertical position as shown in Figs. 2 and 3 toward a horizontal position as shown in Figs. 4 and 5 70 reaching the complete horizontal position shown in said figures as the lazy tong levers reach the fully extended position shown.

The link connections 40 between the brackets 23 and the slats 34 will cause the slats to slowly 75 turn upon their axes so that the slats will be

located substantially flatwise to the window as best shown in Fig. 5 when the lazy tongs reach the fully extended position.

If it is desired to tilt the slats axially to the edgewise position shown in Figs. 6 and 7 or to 5 any intermediate position between that and the position shown in Fig. 5, when the lazy tong evers are fully extended or are at any position between the retracted and fully extended position, a quarter turn backward upon the shaft 10 15 will tilt the lazy tongs back to vertical position as shown in Figs. 6 and 7 and swing the slats to edgewise position relative to the window as shown in said figures.

If it is desired to tilt the slats to a less degree 15 the rod 15 should be given less than a quarter turn proportionate to the amount of tilt desired.

When it is desired to again retract the shade to the position shown in Figs. 2 and 3, rotation of the shafts 15 and 17 in the proper direction will 20 retract the lazy tongs and move the brackets 23 and slats 34 into the retracted position edgewise to the window as shown in Figs. 2 and 3.

It should be noted that the lazy tongs are limited to only a quarter-turn around the rod 15 by 25 means of the stops 43 and 44 at the bottom and front side respectively of the bracket 16 for contact with the angular end portion of the bracket 25.

I claim:

1. A window shade comprising a rod located at one side of a window opening, a series of lazy tong levers located parallel to said rod, brackets connected at spaced intervals upon said lazy tong levers and slidably mounted upon said rod, slats connected at their ends to said brackets, and means for operating said lazy tong levers to slidably move the brackets upon the rod. 35

2. A window shade comprising a rod located at one side of a window opening, a series of lazy 40 tong levers located parallel to said rod, brackets connected at spaced intervals upon said lazy tong levers and slidably mounted upon said rod, slats axially pivotally connected at their ends to said brackets, means for axially tilting said slats, and 45 means for operating said lazy tong levers to slidably move the brackets upon the rod.

3. A window shade comprising a rod located at one side of a window opening, a series of lazy 50 tong levers located parallel to said rod, brackets connected at spaced intervals upon said lazy tong levers and slidably mounted upon said rod, slats axially pivotally connected at their ends to said brackets, means for moving the lazy 55 tong levers around the rod, means operated by the moving of the lazy tong levers around the rod for axially tilting the slats, and means for operating said lazy tong levers to slidably move the brackets upon the rod.

4. A window shade comprising a rod located 60 at one side of a window opening, a series of lazy tong levers located parallel to said rod, brackets connected at spaced intervals upon said lazy tong levers and slidably mounted upon said rod, slats axially pivotally connected at their ends to said brackets, means for moving the lazy 65 tong levers around the rod, links connected to the slats and to the brackets for axially tilting the slats, and means for operating said lazy tong levers to slidably move the brackets upon the 70 rod.

5. A window shade comprising a screw threaded rod located at one side of a window opening, a series of lazy tong levers located parallel to said rod, brackets connected at spaced intervals 75

upon the lazy tong levers and slidably and rotatably mounted upon said rod, one of said brackets having a threaded connection with the screw threaded rod, slats connected at their ends to

5 said brackets, and means for rotating said rod to operate the lazy tong levers and slidably move the brackets upon the rod.

6. A window shade comprising a screw threaded rod located at one side of a window opening, a series of lazy tong levers located parallel to said rod, brackets connected at spaced intervals upon the lazy tong levers and slidably and rotatably mounted upon said rod, one of said brackets having a threaded connection with the 10 screw threaded rod, slats axially pivotally connected at their ends to said brackets, means for rotating said rod to operate the lazy tong levers for slidably moving the brackets upon the rod, and means controlled by the operation of the 15 lazy tong levers for moving the lazy tong levers around the rod and axially tilting the slats.

7. A window shade comprising a screw threaded rod located at one side of a window opening, a series of lazy tong levers located parallel 20 to said rod, brackets connected at spaced intervals upon the lazy tong levers and slidably and rotatably mounted upon said rod, one of said brackets having a threaded connection with the screw threaded rod, slats axially pivotally connected at their ends to said brackets, means for 25 rotating said rod to operate the lazy tong levers for slidably moving the brackets upon the rod, means controlled by the operation of the lazy tong levers for moving the lazy tong levers around 30 the rod and links connected to the slats and to the brackets for axially tilting the slats.

8. A window shade comprising rods located at opposite sides of a window opening, a series of lazy tong levers located parallel to each rod, brackets connected at spaced intervals upon said 35 rods, slats connected at opposite ends to brack-

ets and means for simultaneously operating both series of lazy tong levers to slidably move the brackets upon the rods.

9. A window shade comprising rods located at opposite sides of a window opening, a series of 5 lazy tong levers located parallel to each rod, brackets connected at spaced intervals upon said lazy tong levers and slidably mounted upon said rods, slats axially pivotally connected at opposite ends to the brackets, means for simultaneously operating both series of lazy tong levers to 10 slidably move the brackets upon the rods, and means associated with one series of lazy tong levers for axially tilting the slats.

10. A window shade comprising rods located 15 at opposite sides of a window opening, a series of lazy tong levers located parallel to each rod, brackets connected at spaced intervals upon said lazy tong levers and slidably mounted upon said rods, slats axially pivotally connected at opposite 20 ends to the brackets, means for simultaneously operating both series of lazy tong levers to slidably move the brackets upon the rods, and links connected to the slats and to one series of brackets for axially tilting the slats. 25

11. A window shade comprising a screw threaded rod located at one side of a window opening, a series of lazy tong levers located parallel to said rod, a friction connection between the rod and the lazy tong levers, brackets connected at 30 spaced intervals upon the lazy tong levers and slidably and rotatably mounted upon said rod, one of said brackets having a threaded connection with the screw threaded rod, slats axially pivotally connected at their ends to said brackets, 35 means for rotating said rod to operate the lazy tong levers for slidably moving the brackets upon the rod, and means controlled by the operation of the lazy tong levers for moving the lazy tong levers around the rod and axially tilting the slats. 40
